MACHINE FOR ASSEMBLING OPHTHALMIC MOUNTINGS

Filed July 1, 1932

UNITED STATES PATENT OFFICE

1,978,890

MACHINE FOR ASSEMBLING OPHTHALMIC MOUNTINGS

Samuel E. Bouchard, Rochester, N. Y., assignor to
 Bausch & Lomb Optical Company, Rochester,
 N. Y., a corporation of New York

Application July 1, 1932, Serial No. 620,452

6 Claims. (Cl. 219—11)

This invention relates to machines for assembling ophthalmic mountings by the application of heat and pressure and is especially adapted for assembling ophthalmic mountings of the type 5 disclosed, for example, in U. S. Letters Patent Nos. 1,878,370 and 1,878,371, both issued on September 20, 1932.

One of the objects of my invention is to provide an efficient and improved device for assembling ophthalmic mountings by the application of heat and pressure. Another object is to provide a device having heated jaws for holding and heating an ophthalmic mounting and means for applying pressure to the mounting. These 10 and other objects and advantages reside in certain novel features of construction, arrangement 15 and combination of parts as will hereinafter be more fully described and pointed out in the appended claims.

20 Referring to the drawing:

Fig. 1 is a side elevation of a machine embodying my invention.

Fig. 2 is a front view of same.

Fig. 3 is a top plan view of same.

25 Fig. 4 is an enlarged fragmentary view illustrating the use of the device.

Fig. 5 is a detail view showing the method of holding the lens and mounting.

A preferred embodiment of my invention is disclosed in the drawing wherein 10 indicates a base having an integral column 11 on which the arm 12 is pivotally mounted as at 13. The column 11 has an integral projection 14 on which is fixedly mounted a block 15 which is made of hard rubber, fibre or the like for a purpose to be hereinafter described. Fixedly mounted on block 15 is the arm 16 which carries a steel jaw member 17 at its free end. Adjustably secured to arm 12 by means of screw 18 is a jaw member 19 which 30 extends downwardly and forwardly at an angle to the vertical as shown on Figs. 1 and 2.

Slidably mounted on the free end of arm 12 is a plunger 20 having a finger piece 21. A similar plunger 22, carrying a finger piece 23, is slidably mounted on arm 16. Coil springs 24 and 25 are positioned, respectively, on plungers 20 and 22 and tend to normally keep the ends of the plungers separated. A slot 26 in arm 12 cooperates with a pin 27 on plunger 20 to limit the 40 movement of the plunger and a similar slot and pin (not shown) limits the motion of plunger 22. A spring 28 connecting the projection 14 and arm 12 tends to normally urge the arm downwardly to bring jaw 19 down toward jaw 17. Pivots mounted on block 15 is a lever 29 having a cam

surface 30 by means of which the arm 12 together with jaw 19 may be raised upwardly against the action of spring 28.

Mounted on base 10 is a suitable transformer 31 which is connected to a source of electrical energy by means of wire 32. Leading out from the transformer 31 are the two wires 33 and 34, the first of which is connected to the arm 12 while the second is connected to arm 16. Since arm 16 is mounted on the block 15, made of hard rubber, fibre or the like, it is electrically insulated from arm 12.

In using the device, an ophthalmic mounting M is placed in position between the jaws 17 and 19 as shown on Figs. 4 and 5. The tension of spring 28 serves to hold the jaw 19 down against the mounting M so that the latter is firmly held in place. In the ophthalmic mountings described in my aforesaid Letters Patent the lens L is secured to the mounting by means of a retaining element R which is formed of a non-metallic substance which is rendered plastic by heat. Such a mounting and lens are held between the jaws 17 and 19 with the shoe S of the mounting abutting against the vertical face of the jaw 17 as shown in Fig. 5.

The switch (not shown) of the electrical circuit is then closed so that current flows through arms 12 and 16 and jaws 17 and 19 and thereby heats the metallic ophthalmic mounting M. This is continued until the heat renders the retaining element R quite plastic whereupon the switch is opened and the two plungers 20 and 22 are moved together, to dotted line position of Fig. 4, to grip a part of the mounting and hold the parts firmly together until the material of the retaining element has cooled and hardened. In the preferred form of my ophthalmic mounting the outer lens strap is imperforate while the inner strap has an aperture through which the retaining element is inserted. Hence when the plungers 20 and 22 are brought together the top plunger 20 serves to force the plastic material of element R into the opening. If the mounting has two apertured straps the material of element R will be compressed between plungers 20 and 22. The plungers 20 and 22 are not heated and hence when they come in contact with the mounting they serve to cool the mounting and hasten the setting of the plastic element. The use and operation of my device will be readily apparent to those skilled in the art.

From the foregoing it will be apparent that I am able to attain the objects of my invention and provide an improved machine for use in assem-

bling ophthalmic mountings by the application of heat and pressure. Various modifications can obviously be made without departing from the spirit of my invention.

5 I claim:

1. A device of the type described comprising a base having a fixed arm, a second arm movably mounted on said base, a jaw carried by each of said arms, yieldable means for urging one jaw 10 towards another whereby an ophthalmic mounting may be held between said jaws, electrical means for heating the mounting held by said jaws, a plunger slidably mounted on each of said arms adjacent to the jaw, said plungers being 15 oppositely disposed and adapted to be moved towards each other to contact with the mounting held by the jaws and yieldable means normally urging said plungers away from each other.
2. A machine of the character described comprising a base, an arm fixedly mounted on said base, a jaw carried by said arm, a second arm movably mounted on said base, said second arm carrying a jaw positioned to cooperate with the jaw on the first named arm to hold an ophthalmic 20 mounting, said jaws being electrically insulated from each other, electrical means for heating a metallic mounting held in said jaws and a pair of plungers movably mounted in opposed relation to each other and carried, respectively, on the 25 two ends of said arms adjacent to said jaws whereby said plungers may be moved into contact with a mounting held by said jaws, and yieldable means for normally holding said plungers out of contact with each other.
3. A machine of the type described comprising a base having an upright column, an arm pivotally mounted on said column, said arm having a jaw, an insulated member carried by said base, a jaw carried by said member, a lever pivotally 30 mounted on said member, said lever having a cam portion, yieldable means normally urging said

arm into contact with said cam portion and means for supplying electrical current to said jaws.

4. A machine of the type described comprising a base having an upright column, an arm pivotally mounted on said column, a member carried by said base, said member being electrically insulated from said base, an arm fixedly mounted on said member, means for moving said first named arm towards said second named arm, each of said arms having cooperating jaw portions for holding an object to be heated and means for supplying electrical current to said jaws.

5. A machine of the type described comprising a base having an integral upright column, an arm pivotally mounted on said column, an insulating member carried by said base, an arm carried by said member, a jaw carried by each of said arms, means for supplying electrical current to said jaws, yieldable means for normally urging said first named arm downwardly and cam means mounted on said member for moving said first named arm against the action of said yieldable means.

6. A machine of the type described comprising a base carrying a fixed jaw, a second jaw movably mounted opposite said fixed jaw, yieldable means normally urging said movable jaw towards the fixed jaw whereby an ophthalmic mounting 100 may be held between the jaws, means for electrically heating the mounting held between the jaws, a plunger slidably mounted opposite said fixed jaw and adjacent to the movable jaw, a coil spring surrounding the plunger and normally urging it away from the fixed jaw and stop means 105 for limiting the movement of said plunger whereby said plunger may be selectively depressed to bring it into contact with the heated mounting held in said jaws.
